UNITED STATES PATENT OFFICE.

JACOB S. JAMMER, OF CUMBERLAND, MARYLAND, ASSIGNOR TO WESTERN ELECTRIC COMPANY, INCORPORATED, OF NEW YORK, N. Y., A CORPORATION OF NEW YORK.

REPEATER CIRCUITS FOR MULTIPLEX SYSTEMS.

Application filed July 8, 1921. Serial No. 482,708.

This invention relates to a repeater circuits, and more particularly to amplifying repeater circuits of the type which comprises a pair of vacuum discharge devices 5 of the grid type having their grid circuits oppositely connected to an input line or circuit. Such repeaters are used in signalling systems for amplifying signalling waves at various points along the transmission line 10 and are especially applicable in multiplex telephone and telegraph systems.

In multiplex systems it is extremely desirable to prevent the repeater from modulating a wave of one frequency by a wave 15 of another frequency. Repeater circuits of the type described tend to cause such modulation. This causes cross-talk and interference between the various channels. In order to prevent modulating action in such 20 a repeater it has been proposed heretofore to use in the plate circuits of each of the vacuum tubes constituting one stage of the repeater a choke coil of high inductance. Such choke coils are located in shunt to the 25 alternating current output circuit. It has been found that their use results in much more nearly distortionless repeating and hence less intermodulation of waves of different frequencies. On account of the large 30 number of turns necessarily included in the windings of such coils in order to produce the required inductance an iron core of considerable size must be provided to carry the flux resulting from the direct current 35 through the coil; otherwise with a small core, the core would be magnetically saturated with a consequent loss of inductive effect. The cost of coils for such purposes may be decreased by decreasing the size of 40 the core. To gain this and other advantages it is proposed herein to use a single coil in place of the two coils heretofore used. By passing the direct space current of one tube through one half of the turns in such a 45 direction as to tend to set up a flux in opposition to that set up by the current in the other half the normal flux in the coil is reduced to zero. The core may therefore be only sufficiently large to carry the maximum 50 flux resulting from the currents produced by signalling electromotive forces impressed upon the coil. Thus, there is accomplished with a single small core what has been previously accomplished in such distortionless repeaters with two large core coils. Fur-

thermore, and what is of some importance, experimental tests have indicated a further reduction in distortion with this arrangement as compared with that wherein two coils are used, other conditions being similar. It will be noted that the advantages 60 of keeping the direct space current paths separate from the alternating space current paths are retained. Furthermore the advantage of using the space current source 65 of the repeater as a common space current supply to other repeaters in the same station is also retained. Except for the resistance drop in the choke coil itself the total electromotive force of the space current source 70 is impressed on the tubes. An important essential of distortionless repeaters of the kind described is that the two sides of the circuit must be balanced with respect to each other, with respect to ground, and with 75 respect to the incoming and outgoing lines. The difficulty of maintaining this balance is not increased by the means described herein. The invention is described below in detail 80 in connection with the accompanying drawing, which is a circuit diagram of a two-stage repeater having the characteristically novel features of the invention applied to the output circuit of the first stage.

The repeater circuit is intended to repeat 85 signalling waves from the input line 1 to the output line 2 with amplified energy. The input line 1 is coupled by means of a transformer 3 having a divided secondary winding to the grid circuits 4 and 5 of the tubes 90 6 which comprise the first stage of the repeater. The plate electrodes or anodes 7 of the tubes are connected together through the alternating current output circuit which comprises condensers 8 and impedance elements 9. Under some circumstances the impedance elements 9 may be resistance elements, but if desired the switches 10 may be moved to place in circuit the inductive impedance elements 11 in place of the elements 95 9. When inductance elements 11 are in circuit the variable taps on the elements 9 may be moved to cut out of circuit all or a part 100 of the elements 9 as may be desired.

The anodes 7 are connected together 105 through the inductive choke coil 12 which has two parts 13 and 14. The parts 13 and 14 typify any equivalent arrangement of coils having a high ratio of mutual inductance as compared with their self inductance. A 110

connection 15 extends from the electrical midpoint of the coil 12 to the positive side of a space current battery 16. Space current is supplied to the tubes 6 through the connection 15 and the two halves of the winding of the coil 12 is parallel, each half constituting the path to one tube. The normal flux in the core of the coil 12 will be zero, provided equal currents traverse the two halves of the coil, since these currents pass around the coil in opposite directions. A condenser 17 is shunted around the battery 16. The battery 16 may be used for other repeaters in the same station as indicated by the circuit 18 which may extend to as many repeaters as the battery 16 can supply, the return path for each being through ground.

A second stage of the repeater is provided for reamplifying the output of the first stage before impressing it upon the output line 2. This second stage consists of the vacuum tubes 19 whose grid circuits are connected to the energy transferring impedances 9 or 11, and whose anode circuits 20 are coupled to the output line 2 through the transformer 21.

Since any modulated waves produced in the first stage of the repeater are amplified by the second stage they are much more troublesome than would be modulated waves produced in the second stage; hence the invention as exemplified by the coil 12 has not been applied to the anode circuits of the tubes 19. Furthermore if a high mutual inductance exists between the halves of the primary of the transformer 21, this will tend to reduce modulation in the second stage. Nevertheless the invention could be applied to the second stage of the repeater system in the same manner in which it is applied to the first stage, if desired. Such application is believed to be obvious, and it is therefore not described. It should be said, however, that modulated waves produced in the first or foremost stages of a plural stage repeater cannot be eliminated by applying the invention to the last or succeeding stages, since, in general, except as equalizing or discriminating net works are used between

stages the components present in the output of any particular stage are equally amplified in a succeeding stage or stages. For this reason it is more essential, as stated above, to eliminate modulation and distortion in the first stage of a repeater, than it is to eliminate it in the succeeding stages.

Having described one form of the invention in detail, the novel features believed to be inherent therein will be set forth in the appended claim.

What is claimed is:

An amplifier circuit for preventing modulation during repeating and comprising a pair of space discharge devices, each having a cathode, an anode and a grid element, an incoming circuit, an outgoing circuit, means connecting said incoming circuit differentially to the grid and cathode elements of said two devices, means connecting the cathode and anode elements of said devices equally and oppositely to said outgoing circuit, said last mentioned means including a coupling impedance with its mid-point connected to the cathodes of said devices and having its outer terminals connected through respective wave transmission paths to the anodes of said devices, and means supplying space current between the cathodes and anodes of said devices comprising a source of current and a pair of windings on a unitary core, said windings having a common terminal connected through said source of current to said cathodes and the outer terminals connected to said anodes, the direction of said windings being such that the windings offer low impedance to current components of the same sign flowing simultaneously between their common terminal and the outer terminals but offering high impedance to components tending to flow from one anode terminal to the other whereby said winding and core structure discriminates against the transmission to the outgoing circuit of the undesired components with respect to the desired components.

In witness whereof, I hereunto subscribe my name this 30th day of June A. D., 1921.

JACOB S. JAMMER.
